DYNAMOELECTRIC MACHINE

Martin P. Winther, Waukegan, Ill., and Anthony Winther, Kenosha, Wis., assignors to said Martin P. Winther, as trustee

Application September 13, 1945, Serial No. 616,122

1 Claim. (Cl. 172—284)

1
This invention relates to dynamoelectric machines, and with regard to certain more specific features, to eddy-current slip couplings, brakes, dynamometers and the like.

Among the several objects of the invention may be noted the provision of a dynamoelectric machine for clutches, brakes, dynamometers and the like in which is obtained a torque-speed curve which is flatter over a wider speed range than heretofore; the provision of a machine of the class described which within wide speed limits will generate or transmit torque in substantial proportion to magnetic excitation; the provision of a machine of this class which on the torque-speed curve has a very steep rising torque characteristic under initial slip speed conditions, whereby is left an increased length for the flat portion of the curve; and the provision of a machine of this class which requires no relatively movable regulating means to bring about said improvements. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which several of various possible embodiments of the invention are illustrated,

Fig. 1 is a longitudinal section of typical apparatus embodying the invention;

Fig. 2 is a right-hand elevation of Fig. 1 but showing only the field member;

Fig. 3 is a fragmentary developed view taken on line 3—3 of Fig. 2;

Fig. 4 is a chart showing the formulation of certain area and torque relationships;

Fig. 5 is a chart illustrating qualitatively comparative torque-speed relationships; and

Fig. 6 is a fragmentary diagrammatic section illustrating another form of the invention.

Similar reference characters indicate corresponding parts throughout the several views of the drawings.

United States Patents 2,106,542; 2,220,007; and 2,367,636 show means for improving torque-speed curves in apparatus of this general class. In 2,106,542 is shown means for overcoming

2
drooping torque characteristics of older machines (note curve II as compared to curve I in Fig. 8 of that patent). In 2,220,007 and in 2,367,636 are shown different means tending to flatten a curve of the character of curve II in Fig. 8 of 2,106,542. Patent 2,367,636 shows the simplest of the last-mentioned means and consists in employing belts of pole-forming teeth on opposite sides of an exciting coil, the adjacent ends of the teeth overlapping the coil and to some extent overlapping one another peripherally. The present invention is a further improvement upon the construction of said 2,367,636 patent in which the curve b of Fig. 10 in said patent is very greatly flattened in its operating range and which has a much steeper initial portion by extending the range of the flatness, and which has a much sharper knee portion. In Fig. 5 hereinafter in comparisons between the curves O—1 and N—2, or between N—1 and N—2 illustrate the differences which will be discussed in detail hereinafter.

Referring now more particularly to Fig. 1, there is shown at numeral 1 a drive shaft which may be connected to a suitable power unit such as a motor or the like. Attached to this shaft is a hub 3 having a peripheral portion 5 to which is bolted a flange member 7. Together the parts 5 and 7 form a groove 9 for holding an annular field coil 11. This field coil is excited from a suitable circuit supplied from a suitable slip-ring circuit (not shown). The character of slip-ring circuits for energizing field coils of this nature is so well-known that further description in this respect is unnecessary. The parts 5 and 7 form a grooved field coil container ring having a U-shaped cross section. The inside or cylindric base part of the U-shape is indicated at 9 and the sides or flanges are indicated at 13 and 15.

From the side flanges 13 and 15 extend interdigitated pole-forming teeth 17 and 19, respectively. These teeth 17 and 19 have root portions connected with the ring parts 13 and 15. Their ends are alternately directed over the outside of the coil 11 which they overlap. These overlapping portions of teeth 17 and 19 are indexed 21 and 23, respectively. The tooth portions 21 and 23 overlap the coil and they overlap one another in a peripheral direction as indicated more particularly in Figs. 1 and 3. As

indicated in Fig. 3, they are of tapered forms with long contiguous edges between them. They extend entirely over the coil 11 and extend beyond it. Further particulars in regard to the teeth are given below.

Mounted on bearings 25 on the hub 3 is a hub 27 of a driven member 28. The latter is formed with suitable V-shaped grooves 31 for V belts 33 by means of which power may be taken from the unit. Within the member 28 are constructed fan blades 35 for cooling purposes. The periphery of the member 28 is attached by welding or the like to an inductor or armature ring or drum 37. Around this drum is located a ring 41 held by keying means 39 and a suitable fit. Member 41 is not necessarily made of the highly magnetic material of which member 37 is made, the latter to be described. Parts 37, 39 and 41 rotate as a unit with member 28. Between the outsides of the teeth 17 and 18 and the inner relatively smooth cylindric surface of the drum 37 is an air gap G which is made as small as may be consistent with maintaining proper mechanical clearances both under cool and hot conditions.

The advantages of the invention are obtained by properly relating the forms of the inductor ring 37, teeth 17 and 18. The materials of which these parts are made are also of some importance, particularly as to the inductor. They should be of high magnetic permeability and low electrical resistance. This is particularly true of the inductor ring. For the purpose, magnetic ingot iron especially made for electrical purposes is best, this being a very pure iron. A typical material on the market is "Armco" magnetic ingot iron, which is approximately 99.84% pure iron. This iron is substantially the purest that can be commercially obtained. It is homogeneous in structure and practically free from occluded gases, blow holes, oxides, slag and segregations which makes it ideal as an inductive element for the purpose in hand. Its maximum phosphorous content should be .015%, the maximum sulphur .040% and a total metalloids, including carbon, manganese, phosphorus, sulphur and silicon, a maximum of 250%. From 20 to 30% of copper is not detrimental but it is not necessary. The electrical resistance is of the order of six times the electrical resistance of pure copper. It should be of a value of 15 to 16 kilogausses under a magnetomotive force "H" of 21 giberts per centimeter.

The reason for the importance of the above type of iron, in the inductor 37 particularly, is that it should be very easy to magnetize to a high degree and still readily lose its magnetism when the magnetizing force is removed.

Another and important feature of the invention, for obtaining the desired results, refers to the form of the magnetic circuit around the coil 11. The field around the coil 11 is generally speaking of toric shape as illustrated by the dash lines in Fig. 1. As indicated in Figs. 2 and 3, tapered alternate north and south polar teeth 17 and 18 point oppositely. The marks N and S indicate north and south polarities respectively. Hence when there is relative movement between the polar teeth and the inductor 37, induced north and south polar regions sweep through given areas in the inductor.

At the median section of the coil 11 these N and S regions are of about equal effect and introduce torque properties analogous to an ordinary salient pole inductive machine, that is, a steeply rising torque-speed curve. Toward the axial ends

or sides of the coil 11 north and south pole characteristics dominate, depending on the side under consideration. For example, in Fig. 3 it will be seen that toward the right, north pole characteristics dominate because of the larger areas at the bases of the north poles as compared to the smaller areas at the ends of the south poles; and toward the left, the south pole characteristics dominate for analogous reasons. Thus, while the inductive effect in the inductor 37 over the center of the coil 11 is most like that of a salient pole machine, gradually toward the opposite ends of the coil the inductive effects become more like (but not the same) as those of a toothed rotor type of machine as in Patent 2,106,542. However, there is a difference in the present construction, due to the alternate extensions of the teeth 21 and 23 being carried substantially across the axial length of coil 11, so that even in or near the planes at the ends of the coil 11 there is some tendency toward reversal of field in the inductor 37. However, this reversal is not complete, as is the case in the central plane of the coil. In the planes adjacent the coil ends one or the other of the north or south polarities preponderates (in Fig. 3 the north polarity on the right and the south polarity on the left).

From the above it is clear that in the central plane of the coil 11 the alternating north and south polar areas of flux emanating from the teeth 17 and 18 are about equal in effect. In the planes at or near the sides of the coil 11 the alternate north and south effects of the teeth are present but their torque effects upon the inductor are different. This alternating north and south polar effect varies in effect from the central plane of the coil to the planes next to the coil ends. Thus the new effect is produced as indicated in Fig. 5.

The forms of the field member and inductor should preferably be as indicated in Figs. 1 and 4, to which the following comments are directed:

The outsides of the tapered teeth 17 and 18 lie essentially on an imaginary cylindric surface near the inner cylindric surface of the inductor 37. The insides of these teeth slope away from the coil 11 as indicated at numerals 18 (for teeth 17) and 20 (for teeth 18). This has the effect of additionally tapering the teeth toward their ends. The total of the outer areas A_2 of the teeth 17 and 18 in said imaginary cylinder is determined arbitrarily, for example, by allowing approximately ten square inches of this outer tooth area for each horsepower of heat loss expected (see Fig. 4). Then the actual area $A_2 = D \times \pi \times W \times .7$; where D is the outside diameter of said imaginary cylinder through the outsides of the teeth 17 and 18 and W is the effective width of the teeth in this cylinder as indicated in Fig. 3. This effective width W is between the ends of the teeth. The small ends of the teeth lie in planes that pass through the roots of the teeth 21 and 23 in the flanges 13 and 15 respectively. It will be seen from the equation for area A_2 that it is in effect the area of a circular cylinder through the outsides of the teeth 17 and 18 multiplied by a factor that takes into account the proper amount of space between teeth, this space having the zig-zag form shown in Fig. 3, of width L. Width L (Fig. 3) should be approximately 20 to 25 times the air gap G (Fig. 1).

In Fig. 3 the arrows from the character A_2 indicate the bounding edges for one pair of the essentially triangular figures that go to make up the area A_2 but it is to be understood that

A_2 is the sum of all such figures around the field. Axially considered the included angles between edges of the essential triangles forming the figures is 60° as shown in Fig. 3. This provides for the wide bases shown making these triangles practically equilaterals.

With the area A_2 obtained by proper choice of D and W, the area of the section A_3 through the bottom of groove 8 in Fig. 1 is to equal $.3 \times A_2$. This area A_3 is the circular sectional area of the 10 U-shaped form 1 for retaining the coil 11. Also, each of areas A_4 and A_5 are to be equal to A_3 . Areas A_4 and A_5 are the areas of the sections indicated in Fig. 1. Area A_4 is the circular right 15 sectional area of the inductor drum 37. A_4 is the sum of the areas through the large bases of either set of teeth 17 or 18. This area A_4 is calculated at about the place where the teeth curve down at their connections with circular parts 13 and 15, respectively.

Area $A_5 = .18 \times A_2$, being the total of the areas of each set of teeth 17 or 18 taken at what will be called the root of the poles which is the sum of these areas in a plane passing substantially through one side of the coil 11.

Equivalent relationships arising from those given above appear in the chart of Fig. 4.

It may be noted that one-half of the area A_2 (Fig. 3) is the sectional area of the effective magnetic air gap of one-half of the poles, that is, of one set of poles, either north or south. This means that the area A_3 is

$$.6 \times \frac{A_2}{2}$$

where

$$\frac{A_2}{2}$$

is the effective area just mentioned. Also, by the same reasoning

$$A_5 = .36 \times \frac{A_2}{2}$$

Thus it is clear that the magnetic path through the flux gap is of greater cross section than the magnetic path through the metal parts of the magnetic circuit indicated at A_3 , A_4 , A_5 and A_6 . But, although it may seem that, on the average, the outer surfaces of the polar teeth next to the inductor drum 37 are not operated at said flux saturation, still, since there are some smaller parts of north poles peripherally adjacent to larger parts of south poles and vice versa, there is a variation in unit density at a given point on a pole surface which aids in producing the desired effect.

A slip coupling built along the above lines has a much flatter torque-speed curve as indicated in Fig. 5. In this Fig. 5 curve O-1 is typical for the older type of machine operating cool without the invention. Curve O-2 is typical of a comparable machine operating cool but built along the lines of the invention. Curve N-1 is typical of an older class of machine operating hot without the invention; and curve N-2 is typical of a comparable machine operating hot and built under the invention. The difference is at once apparent. Curves O-2 and N-2 have much steeper initial portions and much flatter, longer flat portions with sharp knees between the steep and flat portions. This effect is substantially independent of the machine temperature.

It will be understood that the inductor member of the combination may be the driving element and the field member the driven element, instead of the reverse as shown in the drawings. It is also to be understood that either one of the elements may be held stationary while the other is turned in order to apply torque to the former, as for example in the case of a dynamometer or brake application of the invention.

Applications wherein the invention has value are for example in clutches for tension drives in various processes; electric clutch drives for gun sighting; for reversing controls of airplane wings and tail surfaces; ventilating blowers, etc. In many of these applications the desired requirement is that of a torque curve which has a very steep initial rising characteristic of torque versus slip speed and which thereafter bends very sharply and remains virtually flat in the remaining range of the slip speed. In the flat part of such a curve the slip will be about inversely proportional to the magnetization of the field coil.

It is to be understood that although we show the coil 11 excited from an outside electrical source for producing a magnetic condition in the polar teeth 17 and 18, this coil may be omitted by making the annular field member of permanently magnetic material, such as for example the well-known "Alnico" metal (Fig. 6). This is accomplished by substituting for the coil 11 a torus 43 of said permanently magnetic "Alnico" or similar material. In this case the member 43 itself acts as a source for the toric magnetic circuit and also this ring 43 is held clamped in place between cheeks 45 and 47 of magnetic material from which extend the magnetic teeth 49 and 51 corresponding generally in shape to the ones above described. The ring 43 is held clamped between the cheeks by brass studs 53.

In Fig. 6 it will be understood that the support for the field member is the shaft 55 which corresponds to shaft 1 in Fig. 1. The inductor drum is numbered 57 (corresponding to inductor drum 37 in Fig. 1). This drum 57 is mounted on a 40 rotary support 59 (corresponding to the member 29 in Fig. 1). Further elaboration of the Fig. 6 alternative will not be necessary in view of the description already given in respect to the preferred form of the invention. It should, however, be noted in Fig. 6 that the toric field, indicated by the dash lines, is completed in part through the permanent annular magnet 43. The section of this annular magnet 43 should preferably be arranged so that the optimum magnetic areas are obtained as above described.

It should be understood in regard to both forms of the invention that while the stated areas are important, many of the advantages of the invention are attained by the use of other areas, 60 the primary feature being that the polar teeth extend substantially entirely across the annular field member and are tapered in opposite directions.

In view of the above, it will be seen that the 65 several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

Dynamoelectric apparatus comprising relative- 75 ly rotary driving and driven members, one of said

members consisting of an inductor member having a substantially uninterrupted homogeneous eddy-current inductor surface, the other member comprising an annularly formed field-producing member producing a toroidal flux field interlinking said field and inductor members, magnetic poles closely enveloping the annularly formed field member and carrying said toroidal flux field, said poles being formed with oppositely directed interdigitated polar teeth extending between the field member and the inductor member, said teeth being formed substantially as alternately extending equilateral triangles lying adjacent to the inductor member.
